WILLIAM LESLIE EDISON, OF WILMINGTON, DELAWARE, ASSIGNOR TO THE W. L. EDISON MANUFACTURING CORPORATION, OF WILMINGTON, DELAWARE, A CORPORATION OF DELAWARE

SIGNALING SYSTEM

Application filed November 26, 1930. Serial No. 498,281.

This invention relates to a high frequency alternating current system and more particularly to means for interconnecting the tubes of an amplifying system. The system herein disclosed is particularly applicable to the amplification of radio signals, the interconnecting means being of a type applicable to the radio amplification stages, preventing oscillation due to mutual reaction.

10 It is the object of the present invention to provide an interconnecting arrangement for the tubes of an amplifying system, and a circuit including such arrangement which produces a high degree of amplification without 15 oscillation, distortion or losses involved in resistance suppression methods heretofore used in radio frequency amplification stages. The interconnecting arrangement specifically 20 consists of a novel element, the construction of which will be clear from the following description read in conjunction with the accompanying drawing, in which:

Fig. 1 is a diagrammatic illustration of a portion of a circuit embodying the improved 25 amplifying system;

Fig. 2 is an elevation of the improved interconnecting element; and

Fig. 3 is a perspective view of a part of the 30 interconnecting element.

Referring first to Figs. 2 and 3, the interconnecting element includes an ordinary tube 2 of insulating material on which is supported a coil 4 of insulated wire, closely or loosely wound depending upon the particular 35 impedance desired, the allowed distributed capacity, etc. A clip 6 of elastic metal of the form shown in Fig. 3 is adapted to clamp the coil and slide thereon as illustrated in Fig. 2, a lead 8 being provided for connecting the 40 slide conductively into a circuit. The clip 6 is separated from the convolutions of coil 4 by the insulations thereon and therefore forms therewith a condenser, the capacity of which depends upon the area of the clip, the dielectric forming the coil insulation, and the

spacing and dimensions of the convolutions. The element, therefore, is, to some extent, equivalent to a portion of a circuit including a condenser having a lead having variable metallic contact by means of a slider clip, or the like, with a coil. However, the novel element offers the advantages that no contact offering indeterminate resistance due to corrosion, pressure, etc. is interposed between the coil and condenser, and that shortened leads 50 are possible because of the simpler arrangement.

The element also offers advantageous dynamic characteristics when incorporated 55 in a circuit in which high frequency oscillations exist.

For example, an amplifying circuit is illustrated in Fig. 1 including the improved elements in several places. In this circuit the coil L_1 of the first element forms a tuned resonant circuit with a variable condenser C_1 , the clip M_1 of the first element being connected to the antenna A. One side of the condenser is connected to the grid of the first tube V_1 , shown in the present instance as a 60 screen grid, heater type tube arranged to be heated by alternating current, although it may be replaced by any other suitable type for amplifying purposes. The other side of the condenser is grounded.

The plate of tube V_1 is connected to the clip M_2 of the second element, the coil L_2 of which, together with variable condenser C_2 , forms a tuned resonant input circuit for tube 65 V_2 . Similar arrangements, the parts of which are correspondingly numbered form the coupling devices between tubes V_2 and V_3 , and V_3 and V_4 , the last being the detector. The output of the detector is amplified by 70 any suitable tube arrangement, the radio frequency choke K confining the high frequency oscillations to the portion of the circuit illustrated. Simultaneous tuning of the 75 resonant circuits is effected by mounting the 80 85 90

movable plates of the condensers C_1 , C_2 , C_3 and C_4 on a common shaft.

When the proper constant voltages are applied to the plates, control grids and screen grids of the tubes in any of the ordinary fashions, the system will operate as an amplifier. The input circuit includes the resonant circuit L_1 — C_1 coupled to the antenna capacity at M_1 and accordingly incoming signals im- 10 press high frequency voltage between the grid and cathode of tube V_1 . The portion of L_1 mutual to the antenna and resonant circuits may be varied by moving the clip along the coil, being maximum and equal to L_1 , when 15 the clip is at the grid end of the coil and zero when the clip is at the grounded end.

In a similar fashion the variable components in the plate circuits of the various tubes produce variable grid potentials in the suc- 20 ceeding tubes through couplings M_2 , M_3 and M_4 . Here also the mutual impedance may be varied by sliding the clips along their respec- tive coils. As a result of the coupling, 25 amplification takes place.

When suitable coils and condensers are used and the clips are properly adjusted, it is found that very stable operation takes place with a minimum of distortion and without re- sistance losses. Sharper selection is also ob- 30 tained. If the circuit tends to become un- stable with change of tubes, readjustment of the clips will bring it back to equilibrium.

The improved interconnecting element has been illustrated in connection with the high 35 frequency amplification stages only since it is practical only in connection therewith. When the clip 6 is of small dimensions of a range useful in practice, the capacity of the small condenser formed by it and the coil is so 40 small that the impedance at low frequencies would be very large. An arrangement offering the proper low impedance for audio fre- quencies would have impractically large dimensions.

In the preferred modification disclosed, the clip is spaced from the metallic convolutions by reason of the fact they are insulated. If bare wire is used for the coil, the spacings of convolutions being used to insulate them 50 from each other, a clip may be used which itself carries spacing insulation in the form of enamel or the like. In some cases an internal clip springing outwardly to conform to the inner surface of the coil supporting tube could be used. However at high fre- 55 quencies the dielectric hysteresis losses in this type of construction would be considerable.

What I claim and desire to protect by Letters Patent is:

60 1. An amplifying system including a ther- mionic tube having cathode, grid and plate elements, a grid circuit joining the grid and cathode of the tube, a coil in the grid circuit, and a conducting member spaced from, but 65 closely adjacent to, convolutions of the coil,

said member being connected to a point the potential of which varies during the operation of the system, the capacity between the member and coil providing a low coupling im- 70 pedance at radio frequencies.

2. An amplifying system including a ther- mionic tube having cathode, grid and plate elements, a grid circuit joining the grid and cathode of the tube, a coil, variations in volt- 75 age in which produce corresponding varia- tions in grid potential, and a conducting member spaced from, but closely adjacent to, convolutions of the coil, said member being connected to a point the potential of which varies during the operation of the sys- 80 tem, the capacity between the member and coil providing a low coupling impedance at radio frequencies.

3. An amplifying system including a ther- mionic tube having cathode, grid and plate elements, a grid circuit joining the grid and cathode of the tube, a coil in the grid circuit, and a conducting member spaced from, but closely adjacent to, convolutions of the coil, 85 said member being connected to a point of varying potential extraneous to the grid circuit, the capacity between the member and coil providing a low coupling impedance at radio frequencies.

4. An amplifying system including a ther- mionic tubes having cathode, grid and plate elements, a grid circuit joining the grid and cathode of the tube, a coil, variations in volt- 95 age in which produce corresponding varia- tions in grid potential, and a conducting member spaced from, but closely adjacent to, convolutions of the coil, said member being connected to a point of varying potential extraneous to the grid circuit, the capacity 100 between the member and coil providing a low coupling impedance at radio frequencies.

5. An amplifying system including a ther- mionic tube having cathode, grid and plate elements, a tuned grid circuit joining the grid and cathode of the tube and including a coil and condenser, and a conducting mem- 110 ber spaced from, but closely adjacent to, con- volutions of the coil, said member being connected to a point the potential of which varies during the operation of the system, the capacity between the member and coil providing a low coupling impedance at radio frequencies.

6. An amplifying system including a ther- mionic tube having cathode, grid and plate elements, a grid circuit joining the grid and cathode of the tube, a coil in the grid circuit, and a conducting member spaced from, but closely adjacent to, convolutions of the coil, and adjustable along the coil, said member being connected to a point the potential of which varies during the operation of the sys- 115 tem, the capacity between the member and coil providing a low coupling impedance at 120 radio frequencies.

7. An amplifying system including a thermionic tube having cathode, grid and plate elements, a grid circuit joining the grid and cathode of the tube, a coil, variations in voltage in which produce corresponding variations in grid potential, and a conducting member spaced from, but closely adjacent to, convolutions of the coil, and adjustable along the coil, said member being connected to a point the potential of which varies during the operation of the system, the capacity between the member and coil providing a low coupling impedance at radio frequencies. 5 70
- 10 75
8. An amplifying system including a thermionic tube having cathode, grid and plate elements, a grid circuit joining the grid and cathode of the tube, a coil in the grid circuit, and a conducting member spaced from, but closely adjacent to, convolutions of the coil, and adjustable along the coil, said member being connected to a point of varying potential extraneous to the grid circuit, the capacity between the member and coil providing a low coupling impedance at radio frequencies. 15 80
- 20 85
- 25 90
9. An amplifying system including a thermionic tube having cathode, grid and plate elements, a grid circuit joining the grid and cathode of the tube, a coil, variations in voltage in which produce corresponding variations in grid potential, and a conducting member spaced from, but closely adjacent to, convolutions of the coil, and adjustable along the coil, said member being connected to a point of varying potential extraneous to the grid circuit, the capacity between the member and coil providing a low coupling impedance at radio frequencies. 30 95
- 35 100
10. An amplifying system including a thermionic tube having cathode, grid and plate elements, a tuned grid circuit joining the grid and cathode of the tube and including a coil and condenser, and a conducting member spaced from, but closely adjacent to, convolutions of the coil, and adjustable along the coil, said member being connected to a point the potential of which varies during the operation of the system, the capacity between the member and coil providing a low coupling impedance at radio frequencies. 40 105

11. An amplifying system including a plurality of thermionic tubes each of which has cathode, grid and plate elements, a plate circuit joining the plate and cathode of one tube, a grid circuit joining the grid and cathode of a succeeding tube, a coil, variation in voltage in which produce corresponding variations in the potential of the grid of the succeeding tube, and a conducting member spaced from, but closely adjacent to, convolutions of the coil, said member being connected to said plate circuit, the capacity between the member and coil providing a low coupling impedance at radio frequencies. 120
12. An amplifying system including a plurality of thermionic tubes each of which has cathode, grid and plate elements, a plate circuit joining the plate and cathode of one tube, 125
13. An amplifying system including a plurality of thermionic tubes each of which has cathode, grid and plate elements, a plate circuit joining the plate and cathode of one tube, a grid circuit joining the grid and cathode of a succeeding tube, a coil, variation in voltage in which produce corresponding variations in the potential of the grid of the succeeding tube, and a conducting member spaced from, but closely adjacent to, convolutions of the coil, said member being connected so that variations in potential are produced therein corresponding to variations in potential of the plate of the preceding tube, the capacity between the member and coil providing a low coupling impedance at radio frequencies. 130
14. An amplifying system including a plurality of thermionic tubes each of which has cathode, grid and plate elements, a plate circuit joining the plate and cathode of one tube, a grid circuit joining the grid and cathode of a succeeding tube, a coil, variation in voltage in which produce corresponding variations in the potential of the grid of the succeeding tube, and a conducting member spaced from, but closely adjacent to, convolutions of the coil, and adjustable along the coil, said member being connected to said plate circuit, the capacity between the member and coil providing a low coupling impedance at radio frequencies. 135
15. An amplifying system including a plurality of thermionic tubes each of which has cathode, grid and plate elements, a plate circuit joining the plate and cathode of one tube, a grid circuit joining the grid and cathode of a succeeding tube, a coil, variation in voltage in which produce corresponding variations in the potential of the grid of the succeeding tube, and a conducting member spaced from, but closely adjacent to, convolutions of the coil, and adjustable along the coil, said member being connected to the plate of the preceding tube so as to be at substantially the same potential as the plate, the capacity between the member and coil providing a low coupling impedance at radio frequencies. 140
16. An amplifying system including a plurality of thermionic tubes each of which has cathode, grid and plate elements, a plate circuit joining the plate and cathode of one tube, 145

a grid circuit joining the grid and cathode of a succeeding tube, a coil, variation in voltage in which produce corresponding variations in the potential of the grid of the succeeding tube, and a conducting member spaced from, but closely adjacent to, convolutions of the coil, and adjustable along the coil, said member being connected so that variations in potential are produced therein corresponding to variations in potential of the plate of the preceding tube, the capacity between the member and coil providing a low coupling impedance at radio frequencies.

In testimony of which invention I have hereunto set my hand at Wilmington, Delaware, on this 24th day of November, 1930.
